METHOD OF IMPROVING THE PIEZOELECTRIC PROPERTIES OF CERAMICS

Sadayuki Takahashi and Norio Tsubouchi, Tokyo, Japan, assignors to Nippon Electric Co., Ltd., Minato-ku, Tokyo, Japan

No Drawing. Filed Mar. 20, 1972, Ser. No. 236,491

Int. Cl. C04b 35/46, 35/48

U.S. Cl. 252—62.9

14 Claims

ABSTRACT OF THE DISCLOSURE

Piezoelectric properties of ceramics of the type

(where M is either Nb, Ta or Sb),

(where M is either Nb or Sb),

and $\text{Bi}(\text{Li}_{1/2}\text{M}_{1/2})\text{O}_3\text{-PbZrO}_3\text{-PbTiO}_3$ (where M is either Nb, Ta or Sb) are improved by thermally diffusing Cr in said ceramics whereby to provide an average amount by weight of about 0.05 to 0.5% Cr_2O_3 therein.

This invention relates generally to a method of obtaining piezoelectric ceramics in which mechanical strength against a bending force is large, the mechanical quality factor (Q_m) is small, and the electromechanical coupling coefficient (K_r) is large. Such ceramics are suitable for use as piezoelectric elements in wideband wave filters.

The value of K_r of piezoelectric element is an important factor when determining the bandpass width of the filter. The bandpass width can be increased by increasing K_r , but to a limited value. Namely, the value of K_r cannot be larger than 1. For this reason, a ceramic filter or a mechanical filter using a piezoelectric element as its transducer has hitherto been limited in use over a relatively narrow band. For wideband applications, it is the practice to use an LC filter.

Since the recent trend has been to reduce markedly the size of communications equipment, the need for smaller size filters has become quite apparent. In this connection, it has become essential to provide mechanical or ceramic filters for use in wideband applications. Under the circumstances, the piezoelectric element is expected to have a reduced Q_m value. The specific bandwidth (B) of a ceramic filter is expressed by the following equation:

$$B \leq \frac{1}{\gamma} + \frac{1}{Q_m}$$

(where γ is the capacitance ratio).

The capacitance ratio γ is dependent on the value of K_r . The larger the value of K_r , the smaller becomes the value of γ . Practically speaking, the K_r of the piezoelectric element has already reached its maximum available value, and it is difficult to realize a smaller capacitance ratio γ ; whereas, there is no limitation as to smaller values of Q_m . Hence, to obtain a wideband filter having an increased specific bandwidth (B), it is necessary to reduce the value of Q_m .

Ceramic compositions of $\text{PbZrO}_3\text{-PbTiO}_3$,

and $\text{Pb}(\text{Ni}_{1/3}\text{Nb}_{2/3})\text{O}_3\text{-PbZrO}_3\text{-PbTiO}_3$ systems, as well as ceramic compositions of the same systems as these with certain additive elements, exhibit large K_r values above 50%. On the other hand, there are difficulties in satisfactorily reducing the value of Q_m . For example, when

2

Q_m is smaller than 80, the value of K_r is accordingly small.

While PbNb_2O_6 is known as a compound whose Q_m is as small as about 10; its K_r value, on the other hand, is too small and this compound also is impractical for use as a wideband filter element.

It has previously been found by one of the inventors herein that the value of Q_m can be reduced by injecting or incorporating an impurity into the $\text{PbZrO}_3\text{-PbTiO}_3$ system ceramics by thermal diffusion following formation of the system. (Ref: M. Takahashi and S. Takahashi; Japan J. Appl. Phys. 9 (1970) (1006).)

Table 1 below, for example, shows by way of comparison the results of a set of experiments on a ceramic body expressed in terms of $\text{Pb}(\text{Zr}_{0.52}\text{Ti}_{0.48})\text{O}_3$. Some of the ceramic samples were produced by adding Cr_2O_3 as one of the raw materials; while other samples contained Cr_2O_3 which was injected or incorporated therein after production of the ceramics.

20

TABLE 1

	Density (gr./cm. ³)	K_r	Q_m	Dielectric constant (ϵ)
No impurity.....	7.30	0.49	240	1,270
25 Additive of 0.05 weight percent Cr_2O_3	7.58	0.61	720	1,015
Injection of 0.05 weight percent Cr_2O_3	7.41	0.35	80	730
Additive of 0.3 weight percent Cr_2O_3	7.60	0.41	680	720
Injection of 0.3 weight percent Cr_2O_3	7.52	0.25	65	430

As shown in Table 1, the value of Q_m can be reduced by injecting or incorporating Cr_2O_3 into the

35 system ceramics after the system is produced. At the same time, however, the value of K_r is also reduced. Namely, this ceramics is not suited for wideband filter element.

THE INVENTION

40 The ceramic materials improved according to this invention are highly practical for use as the piezoelectric element for wideband filters; with the K_r more than 50% and with the Q_m factor less than 30.

The present invention uses, as base ceramics,

(where M is either Nb, Ta or Sb),

50 (where M is either Nb or Sb),

and $\text{Bi}(\text{Li}_{1/2}\text{M}_{1/2})\text{O}_3\text{-PbZrO}_3\text{-PbTiO}_3$ (where M is either Nb, Ta or Sb), in which systems part of Pb (up to 15%) 55 may be replaced by Sr, Ba or Ca. As the accessory ingredient, 0.05 to 0.5 weight percent Cr_2O_3 is used, which is incorporated into the base ceramics by thermal diffusion.

The base ceramics used in this invention may be produced by well known methods. By way of example, they 60 are produced by weighing and mixing the starting materials, calcining the mixture at about 700 to 1000° C. in an oxidizing or inert atmosphere such as in air or nitrogen for a time more than 30 minutes, crushing the calcined mixture, forming the mixture into a desired shape under a pressure of more than about 100 kg./cm.²; sintering the mixture at about 1000 to 1300° C. in an oxidizing or inert atmosphere for about 30 minutes to 10 hours, and then cooling the sintered body to room temperature. In this process, the calcining may be omitted.

65 Chromium can be thermally diffused into the base ceramics either from a solid phase or a vapor phase. Typically, Cr_2O_3 can be used as a solid source material of the

Cr diffusion. In one example, a paste consisting of Cr_2O_3 powder and a binder is applied to the surface of the base ceramic body. Alternatively, the base ceramic body is buried in a powder of Cr_2O_3 or in a powder of Cr_2O_3 and Al_2O_3 , or sandwiched between two Cr_2O_3 plates. Whatever the form, the base ceramic body and Cr_2O_3 powder or plate is heated at about 900 to 1300° C. in an oxidizing or inert atmosphere to effect the thermal diffusion of Cr into the base ceramic body. It is believed that the oxygen atoms are at the same time diffused into the ceramic body whereby Cr_2O_3 is finally incorporated in the ceramic body. The source of diffused oxygen atoms may be Cr_2O_3 and/or the atmosphere if the oxidizing atmosphere is used. Thermal diffusion of Cr from vapor phase may be carried out, for example, by use of CrCl_3 in vapor form at about 800 to 1300° C. in an atmosphere containing oxygen.

The diffusing process should be continued until the desired average amount of Cr_2O_3 is obtained in the base ceramic body, that is, until the Cr_2O_3 in the ceramics reaches a value of 0.05 to 0.5% by weight of the base ceramics. When an amount of the source of Cr diffusion is controlled to a limited value and the thermal diffusion is continued for a sufficient period of time, Cr_2O_3 is uniformly contained everywhere in the base ceramic body, otherwise, the Cr_2O_3 content tends to be locally high at the part of the base ceramic body near the surface thereof and low at the part remote from the surface. In this case, it is preferred that the local content of Cr_2O_3 be more than 0.001 weight percent at the part where the Cr_2O_3 content is lowest and less than 0.5 weight percent at the most dense part.

In order to reduce the size of the filter, the size of the piezoelectric element must be reasonably small. Piezoelectric elements thinner than 0.1 mm. are often required. Since the mechanical strength against bending (or the deflective strength) of the ceramic materials can be more than 1500 kg./cm.² according to this invention, the ceramic materials are unbreakable when they are shaped into a thin plate.

The improved ceramic materials produced according to this invention are highly suitable for use as small size, wideband filter elements and are capable of a broad range of applications.

DETAILS OF THE INVENTION

As illustrative of this invention, the following examples are given:

niobium oxide (Nb_2O_5), tantalum oxide (Ta_2O_5) and antimony oxide (Sb_2O_3), in powder form. Chromic oxide was thermally diffused into the base ceramics produced from the foregoing materials.

The powders were weighed in accordance to the composition desired and mixed together with pure water or alcohol. The mixed powder was dried and calcined at a temperature of about 700 to 900° C. in air for one hour. The sample was crushed and a small amount of water added following which the crushed material was pressed at 700 kg./cm.² and formed into a disc with a diameter of 20 mm., then sintered at about 1100 to 1300° C. in air for one hour, and cooled to room temperature. The Cr_2O_3 powder was kneaded with a small amount of water and applied to the surface of the sample ceramics. For injection of Cr_2O_3 therewith by thermal diffusion, the samples were subjected to heat treatment at about 1000 to 1200° C. in air for 0.5 to 2 hours. The amount of Cr_2O_3 diffused therein was measured by the extinction light intensity method. Part of the sample ceramics was used for the purpose of measuring the mechanical strength against bending (hereinafter referred to simply as "mechanical strength"). The measurement was based on the method disclosed in "Relation Between Sintering Temperature and Structural Characteristics of Ceramics for Circuit Elements" by Ichiro Ida et al. [Electrical Communication Laboratory, Nippon Telephone and Telegraph Corporation, Research Application Report Vol. 16, No. 6 (1967), pp. 1149-1174]. The rest of the sample ceramics was polished to a thickness of 1 mm. Silver electrodes were attached to the samples by baking, and a DC field of 5 kv./mm. was applied to the samples at 100° C. for one hour as a poling treatment.

After storing the samples for more than 24 hours, the K_r and Q_m factors were measured. Unless otherwise stated, the measured results hereinafter shown are derived from samples produced and treated in the same manner as described for Example 1.

Table 2 shows the measured results of K_r , Q_m and the mechanical strength (deflective strength) of the samples obtained from ceramics expressed by the formula

45 (where M is either Nb, Sb, or Ta, and M' is either Ca, Sr, or Ba; $u+v+w=1$), into which Cr_2O_3 is incorporated by thermal diffusion.

Example 1

Unless otherwise stated, the starting materials of the base materials used were lead monoxide (PbO), calcium carbonate (CaCO_3), strontium carbonate (SrCO_3), barium carbonate (BaCO_3) lithium carbonate (Li_2CO_3),

In Table 2, the samples indicated by sample number with an asterisk are solid solution ceramics of

75 system (where M is either Nb, Ta, or Sb) or of the same system with part of Pb. substituted by Ca, Sr and Ba,

none of these containing Cr_2O_3 . This note is similarly applied to the succeeding examples. From Table 2, it is apparent that K_r is markedly large and Q_m is as small as 85 for the asterisked samples.

However, when Cr_2O_3 is incorporated by thermal diffusion into the ceramics, Q_m is considerably reduced with an unchanged or increased value of K_r .

It is quite apparent that the mechanical strength is considerably increased when Cr_2O_3 is incorporated by thermal diffusion (note Samples 1.10 and 1.18).

Example 2

Table 3 shows the results of experiments on solid solution ceramics expressed by the formula

where M' is Ca, Sr, or Ba, and M is Nb, or Sb; ($u'+v'+w'=1$) into which Cr_2O_3 was incorporated by thermal diffusion.

In this embodiment, Fe_2O_3 is used in terms of weight of FeO as the starting material of Fe .

TABLE 3

2.18	Sr	0.1 Sb	0.02	0.51	0.47	0.1	75	9	-----
2.19*	Ba	0.1 Sb	0.02	0.51	0.47	0	64	90	-----
2.20	Ba	0.1 Sb	0.02	0.51	0.47	0.15	64	8	-----

The above results indicate that the compound of this invention is highly practical when used as wideband filter elements.

In the $\text{Pb}(\text{Li}_{1/4}\text{M}_{3/4})\text{O}_3\text{-PbZrO}_3\text{-PbTiO}_3$ system solid solution (where M may be Nb, Ta, or Sb), the effective range in which the value of K_r is maintained above 50% is given in terms of t , u , v , w and x as indicated below when the ceramics are expressed by the formula

wt. percent Cr_2O_3 (where M' is Ca, Sr, or Ba, and M : Nb, Ta, or Sb).

$$\begin{aligned} 0 &\leq t \leq 0.15 \\ 0.01 &\leq u \leq 0.20 \\ 0.37 &\leq v \leq 0.52 \\ 0.34 &\leq w \leq 0.48 \\ 0.05 &\leq x \leq 0.5 \end{aligned}$$

Outside this range, the value of K_r is decreased, and the effect of expanding the bandwidth of filter is small, even if Q_m is reduced. In other words, the effective range according to this invention should preferably be as specified above. In the succeeding examples, the effective range is defined on the same basis. It is to be noted that the amount of x of Cr_2O_3 mentioned in this and the succeeding examples is of an average value, that is a ratio of the total amount by weight of Cr_2O_3 finally contained in a sample to the weight of the sample.

If Cr_2O_3 is not incorporated in the ceramics by diffusion, the value of K_r is very large. However, the value of Q_m cannot be reduced to below about 90. When Cr_2O_3 is incorporated, the value of Q_m is remarkably reduced with an unchanged or increased value of K_r . Thus, these materials can be used as an excellent wideband filter element.

It is apparent that the mechanical strength is considerably increased by virtue of the presence of Cr_2O_3 (note Sample No. 2.12).

The compositional range where the value of K_r is maintained above 50% is given below in terms of t' , u' , v' , w' and x' .

$$\begin{aligned} 0 &\leq t' \leq 0.15 \\ 0.01 &\leq u' \leq 0.20 \\ 0.42 &\leq v' \leq 0.52 \\ 0.33 &\leq w' \leq 0.48 \\ 0.05 &\leq x' \leq 0.50 \end{aligned}$$

Example 3

Solid solution ceramics expressed by the formula

(where M' is Ca, Sr, or Ba; $u''+v''+w''=1$) were used, into which Cr_2O_3 was incorporated by thermal diffusion. Table 4 shows the relations among the quantity of incorporated Cr_2O_3 , K_r , Q_m and mechanical strength.

TABLE 4

Sample No.	M'	t	u''	v''	w''	Amount of Cr_2O_3 incorporated (x'' wt. percent)	K_r (percent)	Q_m	Mechanical strength (kg./cm. ²)
3.1*			0.35	0.30	0.35	0	62	80	-----
3.2			0.35	0.30	0.35	0.5	62	9	-----
3.3*			0.34	0.40	0.26	0	50	95	-----
3.4			0.34	0.40	0.26	0.4	50	13	-----
3.5*			0.50	0.10	0.40	0	54	80	980
3.6			0.50	0.10	0.40	0.5	55	9	1,500
3.7*			0.55	0.15	0.30	0	52	70	-----
3.8			0.55	0.15	0.30	0.45	55	8	-----
3.9			0.40	0.23	0.37	0	69	65	1,080
3.10			0.40	0.23	0.37	0.2	69	13	1,550
3.11	Ca	0.1	0.40	0.23	0.37	0	61	70	-----
3.12	Ca	0.1	0.40	0.23	0.37	0.25	61	21	-----
3.13*	Sr	0.1	0.40	0.23	0.37	0	58	77	-----
3.14	Sr	0.1	0.40	0.23	0.37	0.35	59	19	-----
3.15*	Ba	0.1	0.40	0.23	0.37	0	58	55	-----
3.16	Ba	0.1	0.40	0.23	0.37	0.3	59	14	-----

Table 4 indicates the fact that in the ceramics in which the Cr_2O_3 was omitted, the value of K_r is increased and the value of Q_m is decreased.

Whereas, when Cr_2O_3 is incorporated thereto by thermal diffusion, the value of Q_m is remarkably reduced with an unchanged or increased value of K_r . At the same time, the mechanical strength is considerably increased (note Sample Nos. 3.6 and 3.10).

The compositional range where the value of K_r is maintained above 50% is given below in terms of t'' , u'' , v'' , w'' and x'' .

$$\begin{aligned} 0 \leq t'' &\leq 0.15 \\ 0.35 \leq u'' &\leq 0.84 \\ 0.10 \leq v'' &\leq 0.30 \\ 0.30 \leq w'' &\leq 0.40 \\ 0.05 \leq x'' &\leq 0.50 \end{aligned}$$

Example 4

Solid solution ceramics expressed by the formula

(where M is Nb, Sb, or Ta, and M' is Ca, Sr, or Ba; $u''+v''+w''=1$) were used, into which Cr_2O_3 was incorporated by thermal diffusion. Table 5 shows the relationship among the quantity of Cr_2O_3 incorporated, K_r , Q_m and mechanical strength.

Example 4

Solid solution ceramics expressed by the formula

(where M is Nb, Sb, or Ta, and M' is Ca, Sr, or Ba; $u''+v''+w''=1$) were used, into which Cr_2O_3 was incorporated by thermal diffusion. Table 5 shows the relationship among the quantity of Cr_2O_3 incorporated, K_r , Q_m and mechanical strength.

TABLE 5

Sample No.	M'	t''	M	u''	v''	w''	Amount of Cr_2O_3 incorporated (x'' wt. percent)	K_r (percent)	Q_m	Mechanical strength (kg/cm ²)

4.12*			Ta	0.10	0.45	0.45	0.35	62	12	1,850
4.13*			Ta	0.08	0.47	0.47	0	51	65	-----
4.14*			Ta	0.08	0.47	0.47	0.3	53	10	-----

As shown in Table 5, when no Cr_2O_3 is incorporated, the value of K_r is large, while the value of Q_m is not reduced below 34. Whereas, when Cr_2O_3 is incorporated by diffusion, the value of Q_m is markedly reduced with an unchanged or increased value of K_r . The mechanical strength is considerably increased.

The compositional range where the value of K_r is maintained above 50% is given as follows in terms of t'' , u'' , v'' , w'' and x'' .

$$\begin{aligned} 0 \leq t'' &\leq 0.15 \\ 0.10 \leq u'' &\leq 0.15 \\ 0.425 \leq v'' &\leq 0.47 \\ 0.425 \leq w'' &\leq 0.45 \\ 0.05 \leq x'' &\leq 0.5 \end{aligned}$$

Although the present invention has been described in conjunction with preferred embodiments, it is to be understood that modifications and variations may be resorted to without departing from the spirit and scope of the invention as those skilled in the art will readily understand. Such modifications and variations are considered to be within the purview and scope of the invention and the appended claims.

What is claimed is:

1. A method of improving the piezoelectric properties of ceramics consisting essentially of the following composition:

where M represents an element selected from the group consisting of Nb, Ta and Sb and u , v and w represent a set of mol ratios having the following relation:

$$\begin{aligned} 0.01 \leq u &\leq 0.20 \\ 0.37 \leq v &\leq 0.52 \\ 0.34 \leq w &\leq 0.48 \\ u+v+w &= 1.00 \end{aligned}$$

comprising the step of incorporating Cr into said ceramics by thermal diffusion to the extent that said ceramics contain Cr_2O_3 in an amount of about 0.05 to 0.5% by weight of said ceramics.

2. The method of claim 1, in which Cr_2O_3 is used as a source of Cr diffusion in said incorporation step.

3. The method of claim 1, in which said incorporating step comprises contacting said ceramics with Cr_2O_3 and then heating said ceramics and Cr_2O_3 at about 900 to 1300° C. in an oxidizing or inert atmosphere for a time sufficient for said ceramics to contain Cr_2O_3 in an amount of about 0.05 to 0.5% by weight of said ceramics.

4. A method of improving the piezoelectric properties of ceramics consisting essentially of the following composition:

where M represents an element selected from the group consisting of Nb and Sb, and u' , v' and w' represent a set of mol ratios having the following relation:

$$\begin{aligned} 0.01 \leq u' &\leq 0.2 \\ 0.42 \leq v' &\leq 0.52 \\ 0.33 \leq w' &\leq 0.48 \\ u'+v'+w' &= 1.00 \end{aligned}$$

comprising the step of incorporating Cr into said ceramics by thermal diffusion to the extent that said ceramics contain Cr_2O_3 in an amount of about 0.05 to 0.5% by weight of said ceramics.

5. The method of claim 4, in which said incorporating step comprises contacting said ceramics with Cr_2O_3 and heating said ceramics and the Cr_2O_3 at about 900 to 1300° C. in an oxidizing or inert atmosphere for a time sufficient for said ceramics to contain Cr_2O_3 in an amount of about 0.05 to 0.5% by weight of said ceramics.

6. A method of improving the piezoelectric properties of ceramics consisting essentially of the following composition:

where u'' , v'' and w'' represent a set of mol ratios having the following relation:

$$\begin{aligned} 0.35 \leq u'' &\leq 0.84 \\ 0.10 \leq v'' &\leq 0.30 \\ 0.30 \leq w'' &\leq 0.40 \\ u''+v''+w'' &= 1.00 \end{aligned}$$

comprising the step of incorporating Cr into said ceramics by thermal diffusion to the extent that said ceramics con-

tain Cr_2O_3 in an amount of about 0.05 to 0.5% by weight of said ceramics.

7. The method of claim 6, in which said incorporating step comprises contacting said ceramics with Cr_2O_3 and heating said ceramics and said Cr_2O_3 at about 900 to 1300° C. in an oxidizing or inert atmosphere for a time sufficient for said ceramics to contain Cr_2O_3 in an amount of about 0.05 to 0.5% by weight of said ceramics.

8. A method for improving the piezoelectric properties of ceramics consisting essentially of the following composition:

$u''\text{Bi}(\text{Li}_{1/2}\text{M}_{1/2})\text{O}_3-v'''\text{PbZrO}_3-w'''\text{PbTiO}_3$
where M represents an element selected from the group consisting of Nb, Ta and Sb and u''', v''' and w''' represent a set of mol ratios having the following relation:

$$\begin{aligned} 0.10 &\leq u''' \leq 0.15 \\ 0.425 &\leq v''' \leq 0.47 \\ 0.425 &\leq w''' \leq 0.45 \\ u'''+v'''+w''' &= 1.00 \end{aligned}$$

which comprises the step of incorporating Cr into said ceramics by thermal diffusion to the extent that said ceramics contain Cr_2O_3 in an amount of about 0.05 to 0.5% by weight of said ceramics.

9. The method of claim 8, in which said incorporating step comprises contacting said ceramics with Cr_2O_3 and heating said ceramics and Cr_2O_3 at about 900 to 1300° C. in an oxidizing or inert atmosphere for a time sufficient for said ceramics to contain Cr_2O_3 in an amount of about 0.05 to 0.5% by weight of said ceramics.

10. A method of improving the piezoelectric properties of a ceramic body consisting essentially of a composition selected from the group consisting of

(A) $(\text{Pb}_{1-t}\text{M}'_t)[(\text{Li}_{1/4}\text{M}_{3/4})_u\text{Zr}_v\text{Ti}_w]\text{O}_3$

where M is selected from the group consisting of Nb, Ta and Sb and M' is selected from the group consisting of Ca, Sr and Ba and t , u , v and w satisfy the following relation:

$$\begin{aligned} 0 &\leq t \leq 0.15 \\ 0.01 &\leq u \leq 0.20 \\ 0.37 &\leq v \leq 0.52 \\ 0.34 &\leq w \leq 0.48 \\ u+v+w &= 1.00 \end{aligned}$$

(B) $(\text{Pb}_{1-t}\text{M}'_t)[(\text{Fe}_{1/3}\text{M}_{2/3})_u\text{Zr}_v\text{Ti}_w]\text{O}_3$
where M is selected from the group consisting of Nb and Sb, and M' is selected from the group consisting of Ca, Sr and Ba, and t , u , v and w satisfy the following relations:

$$\begin{aligned} 0 &\leq t' \leq 0.15 \\ 0.01 &\leq u' \leq 0.2 \\ 0.42 &\leq v' \leq 0.52 \\ 0.33 &\leq w' \leq 0.48 \\ u'+v'+w' &= 1.00 \end{aligned}$$

(C) $(\text{Pb}_{1-t}\text{M}'_t)\{(\text{Ni}_{1/3}\text{Nb}_{2/3})_u\text{Zr}_v\text{Ti}_w\}\text{O}_3$
where M' is selected from the group consisting of Ca, Sr and Ba, and t' , u' , v' and w' satisfy the following relation:

$0 \leq t'' \leq 0.15$
 $0.35 \leq u'' \leq 0.84$
 $0.10 \leq v'' \leq 0.30$
 $0.30 \leq w'' \leq 0.40$
 $u''+v''+w''=1.00$

5 and

(D) $(\text{Pb}_{1-u''-t''}\text{Bi}_{u''}\text{M}'_{t''})[(\text{Li}_{1/2}\text{M}_{1/2})_u\text{Zr}_v\text{Ti}_w]\text{O}_3$

where M is selected from the group consisting of Nb, Sb, Ra, and M' is selected from the group consisting of Ca, Sr and Ba, and t'' , u'' , v'' , and w'' satisfy the following relation:

$$\begin{aligned} 0 &\leq t'' \leq 0.15 \\ 0.10 &\leq u'' \leq 0.15 \\ 0.425 &\leq v'' \leq 0.47 \\ 0.425 &\leq w'' \leq 0.45 \\ u''+v''+w'' &= 1.00 \end{aligned}$$

which comprises the step of thermally diffusing Cr into said ceramic body to the extent that said ceramic body contains Cr_2O_3 in an amount of 0.05 to 0.5% by weight of said ceramic body.

11. The method of claim 10, in which Cr_2O_3 is used as a source of the Cr diffusion in said diffusing step.

12. The method of claim 11, in which said diffusion step comprises contacting said ceramic body with Cr_2O_3 and heating said ceramic body and Cr_2O_3 at about 900 to 1300° C. in an oxidizing or inert atmosphere for a time sufficient for said ceramic body to contain Cr_2O_3 in an amount of about 0.05 to 0.5% by weight of said ceramic body.

13. The method of claim 11, in which said diffusion step comprises covering the surface of said ceramic body with a powder comprising Cr_2O_3 and heating said ceramic body and said powder at about 1000 to 1200° C. in air for a time sufficient for said ceramic body to contain Cr_2O_3 in an amount of about 0.05 to 0.5% by weight of said ceramic body.

14. The method of claim 10, in which said diffusion step comprises diffusing Cr from a vapor phase in an oxidizing atmosphere.
